(57) **CLAIM**

The ornamental design for a chair, as shown and described.

DESCRIPTION

FIG. 1 is a perspective view of a chair from the front and left side, showing my new design;

FIG. 2 is a front elevational view thereof;

FIG. 3 is a rear elevational view thereof;

FIG. 4 is a top plan view thereof; and,

FIG. 5 is a left side elevational view thereof, it being understood that the right side is a mirror image of the side shown except for the absence of the lever depicted in broken lines.

The broken line showing of the lever in FIGS. 1, 2, 3, and 5 is for illustrative purposes only and forms no part of the claimed design.
